BOTTLE CARRIER

Albert Wesselman, Cincinnati, Ohio

Application November 3, 1944, Serial No. 561,711

5 Claims. (Cl. 224—45)

1

This invention relates to improvements in a bottle carrier, and is concerned particularly with a carrier constructed of paper board or like material from which the essential elements of the carrier may be formed by merely cutting, scoring, and bending the material of the carrier.

One object of the present invention is to provide a carrier of the kind referred to, with separators for all the bottles accommodated thereby, said separators being formed wholly and entirely from the carrier body or blank from which the carrier is set up, and arranged to snugly support a plurality of bottles against rattle, injury, and defacement in transit.

Another object of the invention is to provide partition walls and partition wings in a bottle carrier, so related to one another as to automatically lock the wings transversely to the partition walls, as the carrier is set up for use.

Another object is to gain the stated advantages and objectives without increasing the production cost and the weight of material used in the manufacture of the carriers.

The foregoing and other objects are attained by the means described herein, and illustrated in the accompanying drawings, in which:

Fig. 1 is an end elevational view of the improved bottle carrier.

Fig. 2 is a view, similar to Fig. 1 but partly broken away, showing the carrier as seen from the opposite end.

Fig. 3 is a plan view showing one side of a flattened blank from which the carrier is formed.

Fig. 4 is a view similar to Fig. 3 showing the opposite side of the blank, it being understood that two thicknesses of material are shown in each view.

Fig. 5 is a perspective view of a partition wing.

Fig. 6 is a perspective view of the carrier in the extended or operative condition for carrying bottles, part being broken away to clarify the illustration.

Fig. 7 is an end view of a modified form of the carrier, the partition wings being unextended, or in other words, disposed in the planes of the central partition walls which depend from the carrier apex.

Fig. 8 is a view similar to Fig. 7 showing a second modification incorporating a wire handle.

Fig. 9 is a view similar to Fig. 7 showing a third modification, with a different form of apex mounting the handle.

In the production of inexpensive but efficient paper board bottle carriers, the aim of the manufacturer is to reduce labor, time, and material

2

factors to a minimum, while at the same time incorporating as many desirable features or accessories as is possible, into the structure of the carrier. Thus, the carrier herein illustrated is made collapsible, and may be of one-piece construction; and within the limits of the piece may be furnished with a handle, end straps, partition walls extending lengthwise, and partition wings extending crosswise, for supporting a plurality of bottles and embracing them snugly to prevent rattle, injury, and defacement while being carried. All of these features are incorporated within the limits of a substantially rectangular blank, without appreciable waste, and by means of mere cuts, scores, and bends in the material. Where the parts require attachment or connection, simple and inexpensive staples or other fastening means may be employed, and these may be applied automatically and in regular sequence as the carrier undergoes completion by automatic machinery. The manufacturing procedure in this instance is particularly free of handling and parts-assembling operations, due to the manner in which the blank is cut and scored to provide the various functional elements of the completed carrier.

Referring to Fig. 6, it will be noted that the carrier comprises a bottom 12, and opposite side walls 13 and 14 disposed in substantial parallelism throughout a portion of their height, said walls being turned inwardly at an angle near their upper portions to present sloping portions 15 and 16 meeting at an apex 17. At the apex 17 the side walls may be developed in any one of several ways to be later explained, for providing a means of lifting and carrying the device. By preference, though not of necessity, the inclined or sloping portions of the side walls may be defined by score lines as indicated at 18—18 and 19—19. Along the score lines 18—18, the structure may be provided with staples, stitches or other fastening means indicated at 20, to maintain the continuity of the resultant gable or apex of the carrier.

Each side wall of the carrier is punched or cut to provide a bottle receiving opening 21 which extends lengthwise of the wall and is bounded at its ends by suspension straps 22 which are integral with the carrier body. The width of the bottle receiving opening may be established between the score lines 18 and 19 of the carrier sides. It is contemplated bottles will be insertable and removable through the openings 21 at opposite sides of the apex, in substantially the manner illustrated by Wesselman Patent No.

2,263,411 dated November 18, 1941, and as described therein. The length of the bottle receiving opening at each side of the carrier, is somewhat less than the combined diameters of the three bottles to be received therein, in order that the upper shoulder portions of the bottles may impinge against the inner edges of straps 22, thereby crowding the bottles firmly toward one another lengthwise of the carrier in order to preclude rattle and displacement. In order to complete the snug reception of the bottles within the carrier, the width of the bottom 12 will preferably be no greater than, and possibly slightly less than, the combined diameters of two bottles disposed at opposite sides of the carrier with their diameters extending at right angles to the side walls, along a common line.

With the bottles thusly crowded into the carrier, it is desirable that separators be provided between all adjacent bottles in order to preclude contact and abrasion of one bottle upon another. In the Fig. 6 carrier herein illustrated, seven separators are needed for preventing bottle contact at approximately the locations of the shoulders of the bottles. It is understood that the separators will function with bottles of the straight-sided variety, as well as with those of the peculiar design illustrated in the aforesaid Wesselman Patent No. 2,263,411. In its most desirable form, the carrier will include also an arrangement of end straps 23-24 struck from the sides of the carrier, and fastened together as at 25 for the purpose of precluding displacement of bottles from the otherwise open ends of the carrier. It may be noted that the end straps hinge at the locations 26, and are formed from the material of the side walls without waste or scrap. Other forms of end straps might be provided, if desired, in place of the type illustrated, or in some constructions the end straps may be considered unnecessary, as for example in the Wesselman Patent No. 2,171,615, dated September 5, 1939, wherein the individual bottles are gripped at their bases to preclude shifting.

The main partition which depends from the apex of the carrier and extends lengthwise thereof to substantially bisect the carrier, is constituted of the flaps 27 and 28 which had been punched from the side walls to produce the bottle receiving apertures 21. These partition elements depend from intermediate sections of the scores 19, between the points 29 and 30, thereby providing a substantial mounting for the partition members at the carrier apex. From material at the opposite ends of flap 27 are formed the wing members 31-31, whereas from the other flap 28 the cooperative wing elements 32-32 are developed. It may be noted that the wing elements 32-32 are integral with the flap 28, and are hinged along score lines 33 for displacement from the central area of flap 28 to positions at which the wings 32 extend transversely at substantial right angles.

By referring to Figs. 3 and 4, it will be appreciated that the greatest possible lateral extension of the wings has been obtained from the material of the flaps 27 and 28, by cutting the wings 31 from the end portions of flap 27, whereas the wings 32 are formed from the material at the middle area of flap 28. It is by this mode of wing formation, that wings of sufficient lateral extent may be produced, to reach far enough toward the carrier sides, for separating the bottles at their points of contact while embraced within a bottle receiving opening 21.

In order to effectively separate the three bottles of a row, it is necessary that the wings of each pair 31-32 extend from the main partition a distance greater than half the width of the carrier. That the wings 31 and 32 cooperate for so separating the bottles, is clearly indicated upon Fig. 1. The total reach of the wing spread 31-32 exceeds half the width of the carrier.

In accordance with the present invention, self-locking means associated with the wings and the main partition members serve to hold the wings in the transverse extended position illustrated by Figs. 1 and 6. It is highly desirable that the self-locking means be constituted solely of the material of the wings and the main partition members 27-28, and that the wings themselves be formed wholly from the partition material. Thus, as illustrated by Fig. 4, wings 32 are formed from flap 28 by means of through cuts at 34-34-35 and 36. The cuts at 36 may be in the form of half-circles or the like, located at the side of a hinge line 33 opposite the body of the wing. By means of this construction, head 37 is formed on wing 32, and in the plane thereof so that when the wing is swung about a hinge line 33 in one direction, the integral head 37 will swing in the opposite direction and to the opposite side of the flap. The stated relationship is clearly illustrated at 32 and 37 of Fig. 1.

Referring now to Fig. 3, it will be appreciated that each wing 31 is formed by means of through cuts 38, 39 and 40, the cut 38 terminating in the outer side edge, and the cut 39 terminating in the lower edge of flap 27. The cut 40 is such as to form a head 41 on the wing, and a constricted neck portion 42 between the head and the body of the wing. The neck portion is bounded by resilient tongues 43-43 opposing one another, and spaced apart a distance less than the vertical dimension or width of head 37 formed on each wing 32. The heads of the wings formed from flaps 27 and 28 are joined together by means of staples or other fasteners 44 and 45, so that the wings thereby joined together may be swung unitarily or as a single transverse partition, to the extended position illustrated by Figs. 1 and 6. That is to say, if the wing 32 of Fig. 6 be grasped and moved about its hinge 33, the wing 31 fastened thereto as at 44 will move in correspondence therewith.

The self-locking means previously mentioned herein, is constituted of the resilient opposed tongues 43-43 of flap 27, and the head 37 of wing 32 (Fig. 6). Since the space between tongues 43-43 is somewhat less than the vertical dimension of head 37, the act of rotating wing assembly 31-32 from the flat position to the transverse extended position, will be opposed by head 37 tending to laterally displace the tongues 43-43. The tongues will readily displace laterally when the wing assembly is so swung to extended position, but as the wing assembly reaches the full extended position, head 37 will leave the tongues 43 and fall behind them to the condition illustrated by Fig. 6, thereby to effect a lock preventing return of the wing assembly to the flattened condition coplanar with the main partition means. Should it be necessary to disengage the locking means for any reason, that may be accomplished by manually displacing the tongues 43-43 laterally away from head 37, so as to permit the head to pass the locking edges of the tongues indicated at 46. When the wing assemblies are extended as in Fig. 6, the distance 65 between them approximates the diameter of a

bottle located substantially centrally of the receiving opening 21 while resting upon the bottom 12. As will be understood, wings 31 embrace a bottle at one side of the carrier, whereas wings 32 embrace a bottle at the opposite side of the carrier. If three bottles are inserted in the opening 21 at opposite sides of the carrier, all of the bottles will be prevented from contacting one another, either by means of the wings, or the flaps 27 and 28 which constitute the main or central partition.

In order to preclude separation of the flaps 27 and 28 as the wing assemblies are disposed toward the transverse position, one or more fasteners or securing means 47 may be driven through said flaps. It is important that flaps 27 and 28 be held together in flatwise relationship, in order to render effective the resiliency of tongues 43 for locking the wing assemblies in the extended or transverse position. If necessary, due to the nature of the material constituting the flaps, several fasteners or adhesive means could be employed around and about the locality of tongues 43, to ensure against separation of the flaps at those locations. In some instances, it may suffice to simply fasten together the lower edges of the flaps constituting the main partition.

Referring to Fig. 1 it may be noted that the bottom of the carrier is constituted of two opposed flaps or sheets 50—50 overlapped as at 48 and joined together by means of a suitable fastener such as a staple or other means 49. These bottom members will preferably be continuous with the sides of the carrier and with the handle portions indicated at 51. If the carrier be of one-piece construction, the handle portions 51 may be joined as indicated at 52 of Fig. 1, however, the connection at 52 is not absolutely necessary in view of the connections at 20. The opposite panels at the handle portions may be apertured at 53 to provide hand holds, as indicated, or in an alternative construction the handle portions may be dispensed with or modified in accordance with Figs. 8 and 9, when it is desired to furnish the carrier with handles of wire or similar material. It will be appreciated, of course, that the carrier of Figs. 1-6 may be constructed of a single blank folded along its medial line, or along a line corresponding to the score line indicated at 54 of Fig. 7, so that the bottom of the carrier will include no joint whatever. In such case, the opposite ends of the blank constituting the carrier will coincide at the top of the handle portion 51. Such a construction is illustrated by Fig. 7, wherein 54 indicates the medial score line of the carrier blank, and 55 indicates the free upper or terminal ends of the blank. Fig. 7 is otherwise identical to Fig. 1, even though the separator wings are not shown in their extended or transverse position.

In accordance with Fig. 8, the main partition members are indicated by the characters 121 and 122, which are identical to the members 21 and 22 of Fig. 6 in all respects. The apex portion of the Fig. 8 carrier, however, is modified and provided with perforations to receive a wire handle 56.

In the Fig. 9 modification, all of the features of Fig. 6 are included except the integral handle portion, this being in Fig. 9 replaced by extensions 57 of limited height, perforated at 58 to receive a wire handle 59. The apex portion of any of the carriers herein illustrated is capable of considerable modification, and in this respect reference may be had to my copending applica-

tion Serial No. 519,163 filed January 21, 1944. In constructions such as Fig. 7 illustrates, the handle portions may be bent outwardly as indicated by the broken lines, to overlie the caps of bottles contained therein, to facilitate stacking and transporting of the carrier units.

One of the primary advantages of the present carrier is that the blank from which it is formed can be cut and scored in the flat, that is, before folding to double thickness condition at which the carrier may be said to be collapsed. The cutting and scoring operations may be performed expeditiously by means of a rotary machine employing knives and perforators continuously operating upon wide sheets from which the blanks are cut. In cutting the wings 31 from the flaps 27, complete severance is to be avoided so that the wing will not inadvertently become detached from the flap 27. It is proposed that weak webs or connections be permitted to occur in portions of the cut 40, or at other locations, to hold the wing in place until such time as the blank reaches the stapler which applies the fasteners 44 and 45 to join wings 31 to the wings 32, which latter are definitely hinged at 33 on flap 28. Once the flaps 31 and 32 are joined together, the first movement of the wings toward the transverse position will sever any weak connections between the wings 31 and the flap 27 from which they are struck.

What is claimed is:

1. A bottle carrier comprising in combination, a bottom, and inclined sides having bottle receiving apertures therein, the sides converging above the bottom to provide an apex extending lengthwise of the carrier, a pair of flaps in flatwise contact depending downwardly into the carrier from the apex, to provide a partition for separating the bottles at one side of the carrier from those at the opposite side of the carrier, each of said flaps having opposite end portions and an intermediate middle area, a pair of extendible wings formed from the material at the opposite end portions of one of the flaps, and a second pair of extendible wings formed from the material at the middle area of the other flap, means connecting one wing of one flap to the corresponding wing of the other flap, for unifying movement of wings at opposite sides of the partition, and means on one flap cooperating with a wing of the other flap, for locking the connected wings in a position of extension transversely of the partition.

2. A bottle carrier comprising in combination, a bottom, and inclined sides having bottle receiving apertures therein, the sides converging above the bottom to provide an apex extending lengthwise of the carrier, a pair of flaps in flatwise contact depending downwardly into the carrier from the apex, to provide a partition for separating the bottles at one side of the carrier from those at the opposite side of the carrier, each of said flaps having opposite end portions and an intermediate middle area, a pair of extendible wings formed from the material at the opposite end portions of one of the flaps, and a second pair of extendible wings formed from the material at the middle area of the other flap, means connecting one wing of one flap to the corresponding wing of the other flap, for unifying movement of wings at opposite sides of the partition, and self-locking means associated with the flaps and wings, to maintain an extended condition of the wings transversely of the partition.

3. A bottle carrier comprising in combination, a bottom, and inclined sides having bottle receiv-

ing apertures therein, the sides converging above the bottom to provide an apex extending lengthwise of the carrier, a pair of flaps in flatwise contact depending downwardly into the carrier from the apex, to provide a partition for separating the bottles at one side of the carrier from those at the opposite side of the carrier, each of said flaps having opposite end portions and an intermediate middle area, a pair of extendible wings formed from the material at the opposite end portions of one of the flaps, and a second pair of extendible wings formed from the material at the middle area of the other flap, means connecting one wing of one flap to the corresponding wing of the other flap, for unifying movement of wings at opposite sides of the partition, a flexible tongue on one of the flaps, and a head on the wing of the other flap, said tongue being normally in obstructive relationship with the head but adapted to be flexed by the head as the wings are extended, and abutments on the tongue and the head interlockable upon movement of the wings to extended condition transversely of the walls.

4. An article separator comprising in combination, a pair of separator walls in flatwise contact, each of said walls having opposite end portions and an intermediate middle area, a pair of extendible wings formed from the material at the opposite end portions of one of the walls, and a second pair of extendible wings formed from the material at the middle area of the other wall, means connecting one wing of one wall to the corresponding wing of the other wall, for unifying movement of wings at opposite sides of the

10
15

separator, a flexible tongue on one of the walls, and a head on the wing of the other wall, said tongue being normally in obstructive relationship with the head but adapted to be flexed by the head as the wings are extended, and abutments on the tongue and the head interlockable upon movement of the wings to extended condition transversely of the walls.

5. An article separator comprising in combination, a pair of flexible separator walls in flatwise contact, each of said walls having opposite end portions and an intermediate middle area, a pair of extendible wings cut and severed from the material at the opposite end portions of one of the walls, each of said wings including a body, a relatively smaller head, and a constricted neck joining the body and the head, a flexible tongue formed in the material of the wall by the cut defining the constricted neck of the wing, a second pair of extendible wings partially severed from the material at the middle area of the other wall, the wings of said second pair each comprising a body portion hinged to its wall, and a head extending from said body portion beyond the hinge, the head of the hinged body portion overlying the constricted neck of the severed wing first mentioned and projecting laterally beyond said neck to interlock with the tongue upon movement of the wings unitarily to extended position transversely of the separator walls, and means maintaining the head and neck of the severed wing in flatwise fixed contact upon the head and body portion of the hinged wing, to ensure unitary movement of the wings.

ALBERT WESSELMAN.
